[57] CLAIM

The ornamental design for a thermochromic thermometer, substantially as shown and described.

DESCRIPTION

FIG. 1 is a front perspective view of a thermochromic thermometer showing our new design;
 FIG. 2 is a front elevational view thereof;
 FIG. 3 is a rear elevational view thereof;
 FIG. 4 is a left side elevational view thereof, the right side being a mirror image thereto;
 FIG. 5 is a front perspective view of another embodiment of our new design of FIGS. 1—4;
 FIG. 6 is a front elevational view of FIG. 5;
 FIG. 7 is a rear elevational view of FIG. 5;
 FIG. 8 is a left side elevational of FIG. 5;
 FIG. 9 is a right side elevational of FIG. 5.
